UNITED STATES PATENT OFFICE

2,443,147

ROAD ROLLER DRIVE WHEELS AND
MOUNTINGS THEREFOR

John R. Ritchie, Minneapolis, Minn.

Application December 11, 1943, Serial No. 513,932

6 Claims. (Cl. 180—20)

1

This invention relates to a road rolling machine or a machine for operating on roads and properly preparing the road bed and surfaces thereof. A road rolling machine of the same general type is disclosed in applicant's prior Patent No. 2,024,184, granted December 17, 1935. Such road rolling machines have now been used in large numbers for compacting and surfacing certain kinds of roads. Such a roller has many advantages over a steel roller and will produce a higher degree of compaction than the old type of steel roller. Heretofore these road rollers with pneumatic tires have been in the form of trailers adapted to be pulled by a truck or other traction means.

It is an object of this invention to provide a road roller having a plurality of spaced tire-equipped front wheels, a plurality of spaced tire-equipped rear wheels, said rear wheels being aligned longitudinally of the machine with the spaces between said front wheels, together with means carried by said machine for propelling said machine and for steering said machine.

It is another object of the invention to provide a road rolling machine having a plurality of rear tire-equipped wheels, said wheels comprising pairs of wheels, each pair being mounted on an axle which is oscillatable about a horizontal longitudinal axis, together with means carried by the machine for driving certain of said pairs of wheels.

It is a further object of the invention to provide a road rolling machine comprising a plurality of spaced tire-equipped front wheels, said wheels being arranged in pairs, each pair of wheels being oscillatable as a unit about a horizontal axis extending longitudinally of said machine, all of said wheels being connected to a member oscillatable about a vertical axis together with means for oscillating said member to steer said machine.

It is also an object of the invention to provide a road rolling machine comprising a frame, a plurality of spaced tire-equipped rear wheels including a pair of wheels oscillatable about a horizontal axis extending between said machine and longitudinally of said machine, an axle carrying said pair of wheels, a driving wheel for said axle and a flexible connection between said driving wheel and axle permitting said oscillation of said wheels.

It is more specifically an object of the invention to provide a road rolling machine having a plurality of tire-equipped rear wheels, some of which are arranged in pairs, said pairs being os-

2

cillatable about a horizontal axis extending longitudinally of said machine midway of said wheels, a motor on said machine, means for driving certain of said pairs of wheels from said motor, an axle for each of said pairs, a driving wheel such as a sprocket for said axle, a connection between said driving wheel and axle comprising a member extending about said axle and oscillatable about pins or shafts extending at right angles to each other and connected respectively to said driving wheel and axle.

These and other objects and advantages of the invention will be fully set forth in the following description made in connection with the accompanying drawings in which like reference characters refer to similar parts throughout the several views and in which:

Fig. 1 is a plan view of the road rolling machine of this invention;

Fig. 2 is a view in side elevation as seen from the bottom of Fig. 1;

Fig. 3 is a partial view in front elevation;

Fig. 4 is for the most part a vertical section taken on line 4—4 of Fig. 1 as indicated by the arrows;

Fig. 5 is a horizontal section taken substantially on line 5—5 of Fig. 4 as indicated by the arrows;

Fig. 6 is a partial view in side elevation;

Fig. 7 is a vertical section taken on line 7—7 of Fig. 4 as indicated by the arrows;

Fig. 8 is a rear view of the machine, some parts being broken away;

Fig. 9 is a view partly in rear elevation and partly in vertical section taken on line 9—9 of Fig. 4; and

Fig. 10 is an enlarged partial view of the speed changing gears used in horizontal section.

Referring to the drawings, a machine is shown comprising a frame 10, and while this might take various forms, in the embodiment of the invention illustrated it is shown as comprising horizontally and longitudinally extending angle members 10a at the sides of the frame and transverse channel members 10b. Other transverse angle members 10c and 10d are also shown. The frame 10 forms a body having a chamber 10e therein adapted to receive some substance to add weight to the machine. A front wall 10ee of said chamber extends in curved formation transversely of the machine. A post 11 is disposed between members 10b substantially midway of their ends and will be secured to the frame in any suitable manner as by welding. A shaft 12

is journaled in the post 11 and has secured to

its upper end a segment of a worm wheel gear 13 with which meshes a worm 14 secured to a shaft 15 and disposed in a casing 16. Shaft 15 extends rearwardly at an angle to the longitudinal center line of the machine and is journaled in the upper end of a bracket 17 secured to an angle member 10c. A hand wheel 18 adapted to be turned by the operator is secured to the end of shaft 15. Shaft 12 is connected at its lower end to a member 20 in turn pivotally connected by a pivot 21 to the center of a transversely extending member 24. Member 24 extends transversely of the machine and has rigidly secured thereto downwardly extending frame members 25. Members 25 have pivotally secured thereto on members 26, axle housings 27 each carrying an axle on which are mounted a pair of tire-equipped wheels 23. In the embodiment of the invention illustrated there are three pairs of the wheels 23, which wheels are equally spaced. It will thus be seen that each pair of wheels 23 can oscillate with its housing 27 about the pivot member 26. All of the members 25 and thus all of the wheels 23, will be turned when members 20 and 24 are turned.

A plate 10f is secured between members 10c and 10d some distance below the top of the frame and a motor 30 is mounted on plate 10f. Motor 30 will preferably be of the internal combustion type and has a crank shaft 31 to which is secured a bevelled gear 32. Bevelled gear 32 meshes with larger bevelled gears 33 and 34 secured respectively to shafts 36 and 37, journaled in bearings in a gear casing 39. Clutch mechanisms 40 and 41 are provided, adapted to be operated by clutch forks 42 and 43 respectively, said clutch fork 42 having secured thereto an operating lever 45 which is connected by a bar or rod 46 to the fork 43. A gear 47 is journaled on shaft 37 and continuously meshes with a gear 48 carried on a shaft 49. Gear 48 is connected by a hub 48a to a smaller gear 48b. Gear 48b meshes with a gear 50 on shaft 36. The gear assembly 48, 48a and 48b is splined to reduced portions of shafts 36 and 37. Gear 50 also has a gear portion 50a formed as an internal gear and is adapted to be shifted by means of a lever 51 to surround and mesh with a small gear 47a secured to gear 47. The gear assembly 48 is formed with bevelled pinions 52 which mesh with bevelled gears 54 and 55 secured respectively to shafts 56 and 57. The bevelled pinions 52 and the bevelled gears 54 and 55 form a differential drive for shafts 56 and 57. See Fig. 10. Shafts 56 and 57 are journaled respectively in members 58 and 59 suitably secured to the frame and said shafts have secured thereto sprocket pinions 60.

The frame member includes plates 10g, 10h and 10i and plates 62 are connected respectively to plates 10g and 10h by headed and nutted bolts 63. Plates 62 with plates 10g and 10h respectively form brackets depending from said frame member and said brackets are spaced longitudinally of said frame member. There is a pair of such brackets at each side of the frame member between each pair of the outer rear wheels. The pairs of said brackets are thus spaced transversely of said frame member. Plates 62 have secured thereto in any suitable manner as by welding, the pins or shafts 64. A reinforcing angle member 65 is disposed between the outer ends of pins 64 and plates 62 and is welded thereto. The pins 64 project inwardly through plates 62 and have oscillatably mounted thereon a casing 66 having bearing hubs 66a 75 gage the inner flat faces of bracket portions 87a.

surrounding pins 64 and carrying bushings 67 engaging pins 64. The casing 66 has end hubs 66b, the axes of which extend at right angles to the hubs 66a and hubs 66b have disposed therein bearings 68 which may be of any suitable type such as ball bearings. An axle 70 is journaled in bearings 68 and has adjacent its ends slightly tapered portions 70a to which are secured in any suitable manner as by keys 71 the hubs 72a of wheels 72 shown as equipped with rather large pneumatic tires 73. Hubs 72a are connected to the rim-carrying portions of wheel 72 by circumferentially spaced bolts 74. Plates 75 are secured to the outer ends of hubs 66b by circumferentially spaced headed bolts 76 and oil sealing members 77 are disposed in the ends of plates 75 surrounding axle 70. Plates 79 surround the axle 70 outwardly of portions 79a and engage the outer ends of the central portions of hub members 72a, said plates being held by nuts 80 threaded on the outer ends of axle 70. Nuts 80 may be held by keys or cotter pins 81 extending through portions thereof and through axle 70. The frame includes plate portions 10j which extend downward in diverging relation to within a short distance of the top of hubs 66b. Spaced vertically extending plates 10k are secured to plates 10j and extend downwardly to within a short distance of axle 70. The portions 30 of housing 66 forming the top intermediate portions of the hubs 66a extend inwardly from the outer ends of said hubs to within a short distance of plates 10k where they are provided with short vertical flanges 66dd. Plates 83 have flat flanges secured to the outer sides of plates 10k and have arcuate portions 83a projecting outwardly and in substantial engagement with the tops of flanges 66d which will also be of arcuate form. Reinforcing gusset plates 10m are disposed between plates 10k and 10j and reinforcing connecting members 10n extend between plates 10k. Said reinforcing members will be secured in any suitable manner as by welding. A driving wheel 85 is provided and while this could be of various kinds, in the embodiment of the invention illustrated it is shown as a sprocket wheel over which runs a chain 86 also running over sprocket wheel 60. As shown in Fig. 1 there are two sprocket wheels 60 and there will thus be two driving wheels 85. Also as shown in Fig. 8, there are three pairs of the wheels 72 and thus three of the axles 70. The outside pairs of wheels 73 only are driven. The pair of wheels to the right of the outside pair as shown in Fig. 8, merely have a plain axle housing 84 which is swingable about a pivot pin 89 carried in a depending frame portion 10p. The wheel 73aa to the left of the right hand pair of driven wheels is a single wheel and also has an axle housing 84a rigidly carried 60 in a depending portion 10p of the frame. The wheel 85 has a rather large opening 85a concentric therewith and has secured thereto adjacent either side of said opening brackets 87 by means of headed screws 88. Brackets 87 have cylindrical portions 87a in which are secured pins 92 which project into opening 85a. A ring 90 is provided and the same has radial bores therethrough in which are disposed bushings 91. A pair of bushings 91 surround pins 92 respectively so that ring 90 is oscillatable about the axes of pins 92. The bores in ring 90 are provided with counterbores at their inner ends and bushings 91 have flanges which seat in said counterbores. The heads of bushings 91 on pins 92 engage the inner flat faces of bracket portions 87a.

The axle 70 has projecting bosses 70b at opposite sides having flat faces which engage the ends of the flanges on the other two bushings 91. A pin 93 extends diametrically through axle 70 and is mounted for floating movement, said pin projecting beyond bosses 70b and having end portions extending through bushings 91. The sides of opening 85a form stops for the ends of pin 93.

A seat 95 is provided supported a short distance above frame members 10a by a bar 95a which extends downwardly and is secured to plate 10f. Seat 95 faces toward the center of the machine. The operator is in convenient position for operating hand wheel 18 and for operating the levers 45 and 51.

The machine is used to compact road beds of various kinds and also used to roll the surface of a road. The body of the frame will be suitably loaded to give the desired weight to the machine. The operator will occupy seat 95 and will be in control of motor 30 which will be driven. The gear member 48 gives two speeds. When gears 50 and 48b are engaged there will be one speed used, and when gear assembly 48 is shifted so that internal gear 50a meshes with gear 47a, gear 47 drives gear 48 to give another speed. The operator will operate lever 45 to connect one or the other of clutches 40 or 41 to drive either gear 34 and shaft 36 or gear 33 and shaft 37 so that shaft 31 will be driven to propel the machine forwardly or rearwardly. Shafts 36 and 37 will be driven in relatively opposite directions through bevelled gears 33 and 34 respectively by means of bevelled gear 32. Shafts 56 and 57 will thus be driven as shown, through the differential mechanism described and sprockets 60 will be driven. Sprockets 60 will through the chains 86, drive the sprocket wheels 85. Sprocket wheels 85 will drive the ring 90 through pins 88 and ring 90 will drive axle 70 through the pin 93 extending through and secured to said axle. As stated, housing 66 and thus axle 70 with wheels 72, can oscillate a short distance about pins 64. Provision is made for about one degree oscillation in each direction before the top of hub 66b engages with the frame plates 10j. It will be seen that the ring 90 which can oscillate about both pin 93 and pins 92, forms a flexible connection between the axle 70 and sprocket wheel 85. This flexible connection is provided to permit the desired oscillation of the wheels about pin 64. Ring 90 acts with pins 92 and 93 to form in effect a universal joint between the axle 70 and sprocket wheel 85. Sprocket wheel 85 therefore, need not move out of its vertical plane when the wheels oscillate about pins 64. The oscillation of the pairs of wheels is desired in order to get a better and more uniform bearing of the tires on the surface. The plates 83 form covers for the upper open end of the casing 66, which opening is between the flanges 66dd. Housing or casing 66 is thus kept sealed.

The operator by turning hand wheel 18, turns vertical shaft 12 through the shaft 15 and worm and worm wheel gearing, thus turning members 20 and 24 about the axis of shaft 12. This swings all of the members 25 and the pairs of wheels carried thereby so that the device is steered in the desired direction.

From the above description it will be seen that I have provided a compact and very efficient power driven road rolling machine. Heretofore, these road rolling machines have been constructed so as to be drawn by some tractor. With the present construction the machine can be in-

dividually operated and hence, can be more conveniently brought into many more places than when it had to be pulled by a tractor or truck. A much more perfect control is had of the machine and it can be used to do more efficient work. The machine can be quickly reversed without turning which is a great advantage over the trailer type. Tracks extending transversely in curved form are thus eliminated. The machine is very compact and the parts are conveniently arranged for operation and control. It will be obvious that the device will have a high degree of utility for the purpose intended.

It will of course, be understood that various changes may be made in the form, details, arrangement and proportions of the parts, without departing from the scope of applicant's invention, which generally stated, consists in a device capable of carrying out the objects above set forth, in the parts and combinations of parts disclosed and defined in the appended claims.

What is claimed is:

1. A road rolling machine having in combination, a frame comprising a weighted body, a plurality of pairs of wheels at one end of said frame having road rolling tires thereon, certain of said pairs being driven, pairs of brackets, the brackets of each pair being spaced longitudinally of said frame and depending therefrom between a pair of driven wheels, a housing pivoted to each pair of brackets about an axis extending substantially parallel to the plane of said wheels, spaced bearings in said housing, an axle journaled in said bearings on which said wheels are carried, a pin extending through said axle midway between said bearings and movable longitudinally in said axle in a direction substantially parallel to the plane of said wheels, a driving sprocket disposed in said housing in a plane substantially parallel to the plane of said wheels, said pin being disposed in the plane of said sprocket and in a central opening in said sprocket, a ring surrounding said axle and disposed in said opening having bores into which said pin extends, longitudinally movable pins disposed at right angles to said pin carried by said ring and extending into openings in said sprocket at opposite sides of said axle, and means on said frame for driving each of said sprockets.
2. The structure set forth in claim 1, said housing having hubs in which said bearings are disposed and members depending from said frame adjacent to said hubs for limiting oscillating movement of said housing.
3. The structure set forth in claim 1, the sides of said opening in said sprocket limiting the longitudinal movement of said first mentioned pin in said axle.
4. The structure set forth in claim 1, brackets secured to the sides of said sprocket having bores in which said last mentioned pins are disposed, said pins being limited in their longitudinal movement in one direction by the sides of said opening in said sprocket and in the other direction by said axle.
5. The structure set forth in claim 1, spaced plate-like members depending from said frame at each side of said sprocket respectively and substantially parallel thereto, members extending outwardly at the remote sides of said last mentioned members, said housing having hubs in which said bearings are disposed, the inner ends of said hubs having portions disposed at the lower sides of said last mentioned members and in close proximity thereto.

6. A road rolling machine having in combination, a frame, a plurality of pairs of wheels at one end of said frame, certain of said pairs being driven, a housing disposed between each of said pairs of driven wheels mounted for oscillation about an axis extending substantially parallel to the plane of said wheels, bearings carried by said housing, an axle journaled in said bearings on which said wheels are carried, a sprocket disposed midway between said bearings in a plane substantially at right angles to the axis of said axle, said sprocket having a central opening therein through which said axle passes, a pin extending through said axle at right angles thereto and movable longitudinally, a ring surrounding said axle having bores into which said pin extends, means at opposite sides of said sprocket having bores therein, longitudinally movable pins disposed at right angles to said first mentioned pin and disposed in said bores and extending into bores in said ring, and means on said frame for driving said sprockets.
